(57) **CLAIM**

The ornamental design for a cap for a hand-held electroporation device, as shown and described.

DESCRIPTION

FIG. 1 is a top, left, front perspective view of a cap for a hand-held electroporation device according to our new design;

FIG. 2 is a bottom, left, rear perspective view thereof;

FIG. 3 is a bottom plan view thereof;

FIG. 4 is a top plan view thereof;

FIG. 5 is a right side elevation view thereof;

FIG. 6 is a left side elevation view thereof;

FIG. 7 is a front elevation view thereof;

FIG. 8 is a rear elevation view thereof; and,

FIG. 9 is top, left, front perspective view of the cap for a hand-held electroporation device illustrated in FIGS. 1-8 in a condition of use.

The broken lines in FIGS. 1-8 show portions of the cap for a hand-held electroporation device that form no part of the claimed design. The broken lines in FIG. 9 show environmental structure associated with the cap for a hand-held electroporation device in a condition of use and also form no part of the claimed design.
